Int. Cl. D21—01

U.S. Cl. D34—2 C

FIG. 1 is a side elevational view of a toy animal figure embodying our new design and wherein the opposite side is a mirror image of that shown;

FIG. 2 is a top view of the toy animal figure;

FIG. 3 is a bottom view of the animal figure;

FIG. 4 is a rear elevational view of the animal figure;

FIG. 5 is a front elevational view of the animal figure; and

FIG. 6 is a perspective view of the animal figure.

The broken lines shown in FIGS. 1 and 3 consist of lines of stitching.

We claim:

The ornamental design for a toy animal figure, substantially as shown and described.
